UNITED STATES PATENT OFFICE.

SARAH H. KENDALL, OF DAVENPORT, IOWA, ADMINISTRATRIX OF AMOS M. KENDALL, DECEASED.

BRAKE FOR CARS.

SPECIFICATION forming part of Letters Patent No. 744,079, dated November 17, 1903.

Application filed April 24, 1903. Serial No. 154,067. (No model.)

To all whom it may concern:

Be it known that I, SARAH H. KENDALL, a citizen of the United States, and a resident of Davenport, in the county of Scott and State of Iowa, administratrix for the estate of AMOS M. KENDALL, deceased, do hereby declare that said AMOS M. KENDALL, who was a citizen of the United States, and a resident of Davenport, in the county of Scott and State of Iowa, did invent certain new and useful Improvements in Brakes for Cars, of which the following is a full, clear, and exact description.

The object of said invention is to provide a simply-constructed and effective handle for the shafts of mechanical brakes for cars, and particularly for passenger-cars, whether vestibule or otherwise, which when not in use lies back against the wall of the car in such manner as to leave the platform free and which because of the great leverage its construction makes possible is capable of easy operation with one hand. This is accomplished by the means hereinafter fully described, and as particularly pointed out in the claims.

In the drawings, Figure 1 is a front view of said invention. Fig. 2 is a horizontal section taken on dotted line 2 2, Fig. 1, showing the pawl in engagement with the ratchet. Fig. 3 is a similar view showing the pawl released from the ratchet. Fig. 4 is a front view of the end portion of the lever nearest the brake-shaft, showing the shell thereof in longitudinal central section. Fig. 5 is a plan view showing the lever in a position opposite to that shown in Fig. 1.

In the drawings, A represents a suitable plate, preferably of rectangular proportions, which is secured to the end wall of the car at such height above the platform that the handle of the mechanical brake supported thereby will be within convenient reach of train-hands. Projecting centrally from this plate is a bracket a, which provides a suitable bearing for the upper end of the brake-shaft B, and projecting from the upper right-hand corner of said plate is a release-lug b, the extent of whose projection is considerably less than that of lug a, substantially as shown. The part C of the shaft B journaled in the bearing-boss a is preferably slightly greater

in diameter than the portion below the same, and this enlarged portion extends a short distance above its bearings and serves as a journal for the annular boss or sleeve d, secured to the contiguous end of the plate D, forming the under side of the contiguous hollow end portion e of the lever E. Immediately above sleeve d shaft B is reduced in diameter to form a seat f for the segmental span or sickle-shaped arm g of the trip G, as will hereinafter more fully appear, and above this seat said shaft is provided with a ratchet F. The upper end of the shaft extends slightly above the ratchet F and is preferably reduced in diameter and fits into the socket h, formed in a boss made integral with and arising from the upper side of the contiguous end of the hollow portion e of lever E.

Arising vertically from the end plate D is a vertical post H, in the side of which facing the ratchet it is provided with a longitudinally-extending open bearing m, the entrance to which is less than the diameter thereof, and journaled in this open bearing m is the pintle n of the wing I. Wing I extends from its pintle out through the restricted entrance of the open bearing m and increases in width as it approaches the ratchet and has in its vertical edge an open bearing, similar to that in lug H, in which the pintle of the pawl J is journaled. The pawl J extends a suitable distance toward the rear of the lever and is so shaped that its rear vertical surface is normally in contact with the beveled surface of the contiguous vertical edge of the arm I, (to the rear of the open bearing therein,) and its heel on the opposite side is provided with a V-shaped projection or tooth o, which engages the ratchet, substantially as shown. Pawl J is kept bearing against the ratchet by the pressure of a leaf-spring K, the contiguous end of which presses forward against the rear surface of the wing I, and the opposite end of said spring is secured and held between lugs k' k', projecting vertically from said plate D, near the end thereof opposite the brake-shaft.

The construction of said invention, as hereinbefore described, is such that when the lever is moved from right to left the pawl engaging the ratchet will turn shaft B in the

same direction; but when the lever moves from left to right it will ride over said ratchet preparatory to obtaining a fresh grip upon the same when it arrives at the limit of its 5 left-to-right movement. When it is desired to release or disengage the pawl from the ratchet to permit the shaft to reverse, pressure upon the trip is brought to bear either by hand or in the manner hereinafter referred 10 to. Arm *g* projects from and forms the fulcrum or pivot for the body of trip *G*, which latter is block-shaped and has the outer vertical side thereof rectangular. The portion of this body above the plane of the arm *g* is 15 made thicker, and its inner surface operates as a presser-foot *r*, that normally rests against the front vertical surface of wing *I*. Projecting horizontally and longitudinally from the lower edge of this trip-body in a plane slightly 20 below that of arm *g* is a short handle or arm *R*. Now when it is desired to release the pawl from the ratchet, handle *R* of the trip is when the lever is in the position shown in Fig. 1 pushed to the rear, thus causing the 25 presser-foot *r* to bear against and move arm *I* to the rear and carrying the pawl *J* out of engagement with the ratchet. The same result will be accomplished by throwing the lever around to the limit of its movement from 30 left to right and causing the outer surface of the body of the trip to come in contact with and be depressed by the releasing-lug *g* of plate *A*.

The sides of the end portion *e* of the lever 35 *E* in which the movable mechanism carried thereby is housed consists of a comparatively thin shell, and the longitudinal vertical sides of the same are continuous around the shaft *B* to form an end wall. A portion of this 40 curved end wall extends down to form the drop wall or apron *s*, which surrounds and holds arm *g* of the trip in its seat and overlaps a portion of the sleeve *d*. The side wall of portion *e* of said lever *E* where the body 45 of the trip is located is cut away to accommodate the same.

An important feature of this invention is the fact that, aside from securing the plate *D* to the under side of the portion *e* of the 50 lever *E* by rivets, bolts, or any other suitable manner, very little, if any, machine-work is necessary in the construction of said improved lever and every part of the same is so constructed that it can be removed and replaced 55 by inexperienced persons easily and quickly.

What I claim, and desire to secure by Letters Patent for and on behalf of the estate of the said AMOS M. KENDALL, deceased, is—

1. A brake for cars comprising a lever, a 60 shaft having a ratchet thereon, and a spring-controlled double-jointed pawl connected to said lever and engaging said ratchet.

2. A brake for cars comprising a lever, a shaft having a ratchet thereon, a spring-controlled double-jointed pawl connected to said 65 lever and engaging said ratchet, and a trip for disengaging said pawl from said ratchet.

3. A brake for cars comprising a lever, a shaft having a ratchet thereon, and a double-jointed pawl connected to said lever and engaging said ratchet. 70

4. A brake for cars, comprising a stationary release-lug, a brake-shaft journaled adjacent to and integral with said release-lug, a ratchet mounted on said brake-shaft, a lever, 75 and a pawl connected to said lever and normally engaging said ratchet.

5. A brake for cars, comprising a stationary release-lug, a brake-shaft journaled adjacent to said release-lug and having a ratchet 80 mounted thereon, a lever, and a double-jointed pawl connected to said lever and normally engaging said ratchet.

6. A brake for cars comprising a stationary release-lug, a brake-shaft journaled adjacent to said release-lug and having a ratchet 85 mounted thereon, a lever, and a spring-controlled double-jointed pawl connected to said lever and normally engaging said ratchet.

7. A brake for cars comprising a supporting-plate having a release-lug and having a bearing-bracket projecting therefrom, a brake-shaft journaled in said bearings and having a ratchet mounted thereon, a lever, 90 and a double-jointed pawl connected to said lever, and normally engaging said ratchet.

8. A brake for cars comprising a stationary release-lug, a brake-shaft journaled adjacent to said release-lug and having a ratchet 100 mounted thereon, a lever, a double-jointed pawl connected to said lever and normally engaging said ratchet, and a trip for disengaging said pawl from said ratchet.

9. A brake for cars comprising a stationary release-lug, a brake-shaft journaled adjacent to said release-lug and having a ratchet 105 mounted thereon, a lever, a spring-actuated double-jointed pawl connected to said lever and normally engaging said ratchet, and a trip for disengaging said pawl from said ratchet.

10. A brake for cars comprising a brake-shaft having a ratchet mounted thereon, a lever having the end engaging said shaft hollow, a wing, a post arising from the bottom of 115 said hollow portion of the lever to which said wing is pivotally connected, a pawl pivoted to the end of said wing adjacent to said ratchet, and a spring bearing against said wing and keeping said pawl normally in engagement 120 with said ratchet.

11. A brake for cars comprising a brake-shaft having a ratchet mounted thereon, a lever having the end engaging said shaft hollow, a wing, a post arising from the bottom of 125 said hollow portion of the lever to which said wing is pivotally connected, a pawl pivoted to the end of said wing adjacent to said ratchet, a spring bearing against said wing and keeping said pawl normally in engagement with 130 said ratchet, and a trip pivotally connected to said shaft for disengaging said pawl from said ratchet.

12. A brake for cars comprising a brake-

shaft having a ratchet mounted thereon, a lever having the end engaging said shaft hollow, a wing, a post arising from the bottom of said hollow portion of the lever to which said wing is pivotally connected, a pawl pivoted to the end of said wing adjacent to said ratchet, a spring bearing against said wing and keeping said pawl normally in engagement with said ratchet, and a trip pivotally connected to said shaft and provided with an exterior handle and adapted to disengage said pawl from said ratchet.

13. A brake for cars comprising a brake-shaft having a ratchet mounted thereon, a lever having the end engaging said shaft hollow, a wing, a post arising from the bottom of said hollow portion of the lever to which said wing is pivotally connected, a pawl pivoted to the end of said wing adjacent to said ratchet, a spring bearing against said wing and keeping said pawl normally in engagement with said ratchet, and a trip having a curved arm pivotally connecting it to said shaft, and hav-

ing an exterior handle extending therefrom which is adapted to disengage said pawl from 25 said ratchet.

14. A brake for cars comprising a brake-shaft having a ratchet mounted thereon, a lever having the end engaging said shaft hollow, a wing, a post arising from the bottom of 30 said hollow portion of the lever to which said wing is removably pivoted, a pawl removably pivoted to the end of said wing adjacent to said ratchet, and a spring bearing against said wing and keeping said pawl normally in engagement with 35 said ratchet.

In testimony whereof I have hereunto set my hand, in the presence of two witnesses, this 6th day of April, 1903.

SARAH H. KENDALL,
Administratrix for the estate of Amos M. Kendall, deceased.
